UNITED STATES PATENT OFFICE.

BENJAMIN B. OLSEN, OF MARSHALLTOWN, IOWA.

AIR HEATER.

Application filed February 24, 1921. Serial No. 447,611.

To all whom it may concern:

Be it known that I, BENJAMIN B. OLSEN, a citizen of the United States of America, residing at Marshalltown, in the county of 5 Marshall and State of Iowa, have invented new and useful Improvements in Air Heaters, of which the following is a specification.

The object of the invention is to provide an apparatus for application to an explosion engine of the type used in connection with 10 automobiles, tractors and similar motor actuated vehicles, as a means of supplying heated air to the explosive mixture under conditions controllable by the operator, and 15 in quantities adapted to the load, as a means of increasing the efficiency of the engine and insuring a complete combustion and hence an economy in the use of the fuel; and with these objects in view the invention consists in a construction and combination of 20 parts of which a preferred embodiment is shown in the accompanying drawings, wherein:—

Figure 1 is a side view of an apparatus 25 embodying the invention applied in the operative position to a motor.

Figure 2 is a vertical sectional view of the same on the plane indicated by the line 2—2 of Figure 1.

The device consists essentially of a heater 30 of substantially hook shape in cross section adapted to fit over and be suspended upon and in contact with the exhaust manifold 11 of the motor indicated at 12, said heater having a reduced air inlet 13 and being contracted or reduced in area toward its lower end as shown at 14 and in communication with a nozzle 15 tapping the inlet manifold 16 and provided with a regulating 35 valve 17 from which extends an operating rod 18 adapted to be extended to a position within convenient reach of the operator of the engine or the driver of the car or vehicle, said inlet manifold as in the ordinary 40 construction being in communication with the carbureter indicated at 19.

The heater is provided with longitudinally 45 extended ears 20 for engagement by the inlet clamps 21 which are used to secure the inlet manifold and other parts of the structure in proper relation.

An apparatus such as described will serve to furnish fresh heated air in the desired quantities proportionate to the intake of fuel from the carbureter to increase the efficiency 55 of the explosive mixture, and may be applied to a motor now in use without necessitating any modification in the construction or arrangement thereof other than to tap the wall of the intake manifold for the reception of the threaded extremity 22 of the nozzle 15,—the weight of the heat chamber being supported directly by the exhaust manifold over which it is engaged as indicated 60 in Figure 2. Obviously vibration of the attachment will be prevented by the engagement of the clamps 21 with the ears 20 which are disposed in contact with the wall or surface of the exhaust manifold or any convenient portion of the structure. 65

Having described the invention what is claimed as new and useful is:—

1. An apparatus for the purpose described consisting of a heat chamber of cross sectionally hook shape for supporting engagement with an exhaust manifold and adapted for contact with the wall thereof, said chamber being provided with a reduced air intake port and a valved nozzle in communication with the intake manifold of the engine, said heat chamber having a longitudinally extended transversely arched upper portion and being reduced in area toward its point of communication with said nozzle. 75

2. An apparatus for the purpose described 80 consisting of a heat chamber of cross sectionally hook shape for supporting engagement with an exhaust manifold and adapted for contact with the wall thereof, said chamber being provided with lateral ears on opposite sides for engagement by the exhaust manifold clamps, said chamber being further provided with an air intake port and a valved nozzle in communication with the intake manifold and being of cross sectionally reduced area toward its point of communication with said nozzle. 85 90 95

In testimony whereof I affix my signature.

BENJAMIN B. OLSEN.
